UNITED STATES PATENT OFFICE.

WILLIAM IVOR BELL, OF CHELSEA, LONDON, ENGLAND.

SYSTEM OF STORING MOTOR ROAD VEHICLES.

Application filed September 29, 1928, Serial No. 309,284, and in Great Britain October 12, 1927.

This invention relates to storage systems and has particular reference to garages for motor road vehicles, the object of the invention being to enable a maximum number 5 of units to be stored in a given floor space without detracting from the ability to readily put them in and take them out of store.

The improved system comprises essentially the use of one or more platforms 10 adapted to contain or hold any predetermined number of units to be stored arranged either side by side or in any other suitable and convenient manner. These platforms are capable of being moved over 15 the floor space in a predetermined direction and coating with them are a plurality of travelling trucks arranged to traverse the floor space at right angles to the direction in which the travelling platforms move.

20 The platforms and trucks are all of one height which register with the surrounding floor level so as to present a floor which is level throughout with the exception of the track for the truck at the time being used, 25 and at one end of the platforms is an alley way in which the trucks rest when out of use said space having an entrance at one end and an exit at the other end, the floor spaces between the tracks for the trucks in 30 the alley way being on the same level as the floors of the trucks and platforms.

In order that the invention may be fully understood it will now be more particularly described with reference to the accompanying 35 drawing which shows by way of example a lay out for a garage for road vehicles in which 6 travelling platforms and 4 trucks are employed.

The platforms 1 are each of such a width 40 as will take the desired number of pairs of cars side by side. If this number is say four each platform will accommodate eight cars. The platforms are adapted to run on rail tracks 2 which are arranged in parallel 45 relation to one another and to the common alley way 3. At right angles to the platform tracks 2 are tracks 4 for the travelling trucks 5 said tracks being at a distance apart equal to substantially half the width 50 of the platforms so that when all the platforms are as far as they will go in one direction—shown in the accompanying drawing to the left—the truck 5 on the extreme right hand track 4 can traverse 55 the length of the adjacent platforms on one side thereof. The width of the alley way

3 is sufficiently wide to allow the trucks 5 to be placed clear of the track of the adjacent travelling platforms. Alongside the end or outside tracks for the trucks a limited number of fixed platforms or spaces 6 may be provided.

Both the platforms and the trucks may be moved by any suitable means either 65 manually or power operated.

If desired the trucks can be arranged to tilt to facilitate running the cars off them on to the platform.

It will be understood that the floors of the platforms, the trucks, and the parts of 70 the alley way between the tracks for the trucks are of the same height, and that any number of platforms and/or trucks may be employed in any given floor space.

If the store or garage is on the ground 75 floor and the position of the building will allow it auxiliary doors may be provided to facilitate access to the trucks and/or the platforms.

It will be seen that this system has the 80 great advantage that if the floor space is only partly filled the vehicles may be driven into and out of their storage positions without the use of the trucks or without any movement of the platforms.

85 This system also lends itself to the lock-up system as each space on the platforms may be provided with a lock-up cage.

What I claim is:

1. In a storage system, a building, a plurality of parallel tracks arranged on the available floor space of said building, a plurality of parallel tracks arranged at right angles to the first named tracks, platforms arranged to travel on the first named tracks, 90 trucks arranged to travel on the second named tracks, and a common alley way arranged parallel with the first named tracks, the general arrangement being such that the whole of the available floor space less the 95 space required for one track and the common alley way is employed for storage purposes.

2. In a storage system, a building, a plurality of parallel tracks arranged on the 105 available floor space of said building, a plurality of parallel tracks arranged at right angles to and crossing the first named tracks, a group of platforms arranged to travel on the first named tracks, a plurality of trucks 110 arranged to travel on the second named tracks, and a common alley way arranged

parallel with the first named tracks, the general arrangement being such that the storage receptacles occupy the whole of the available floor space less the space required for 5 one track and the common alley way.

3. In a storage system, a building, a plurality of parallel tracks arranged on the available floor space of said building, a plurality of parallel tracks arranged at right 10 angles to and crossing the first named tracks, a group of platforms arranged to travel on the first named tracks, a plurality of trucks arranged to travel on the second named tracks, a plurality of fixed storage receptacles arranged parallel with the second named tracks, and a common alley way arranged parallel with the first named tracks, the general arrangement being such that the storage receptacles occupy the whole of the available floor space less the space required for 20 one track and the common alley way.

4. In a storage system, a building, a plurality of parallel tracks arranged on the available floor space of said building, a plurality of parallel tracks arranged at right 25 angles to and crossing the first named tracks, a group of platforms arranged to travel on the first named tracks, a plurality of storage receptacles on each of said platforms, a plurality of trucks arranged to travel on the second named tracks, and a common alley way arranged parallel with the first named tracks, the general arrangement being such that the storage receptacles occupy the whole 30 of the available floor space less the space 35

required for one track and the common alley way.

5. In a storage system, a building, a plurality of parallel tracks arranged on the available floor space of said building, a plurality of parallel tracks arranged at right 40 angles to and crossing the first named tracks, a group of platforms arranged to travel on the first named tracks, a plurality of storage receptacles on each of said platforms, a plurality of trucks arranged to travel on the second named tracks, a plurality of fixed storage receptacles arranged parallel with the second named tracks, and a common alley 45 way arranged parallel with the first named tracks, the general arrangement being such that the storage receptacles occupy the whole of the available floor space less the space required for one track and the common alley way. 50

6. In a garage for storage vehicles, the combination of a plurality of travelling platforms each adapted to hold a plurality of vehicles, a plurality of travelling trucks each adapted to hold a single vehicle, said 55 platforms and trucks being adapted and arranged to be capable of movement relative to each other, tracks arranged at right angles to one another on which such platforms and trucks move in such a manner that the trucks can deliver cars on to any desired platform and on to any desired part of any of said platforms. 60

WILLIAM IVOR BELL.
